UNITED STATES PATENT OFFICE.

HEINRICH OSTWALD, OF COLOGNE, GERMANY.

BALL-MILL.

1,043,349.

Specification of Letters Patent.

Patented Nov. 5, 1912.

Application filed May 15, 1911. Serial No. 697,307.

To all whom it may concern:

Be it known that I, HEINRICH OSTWALD, subject of the Emperor of Germany, residing at Cologne, Germany, have invented 5 certain new and useful Improvements in Ball-Mills, of which the following is a specification.

The present invention relates to ball-mills, belonging to one of the most important 10 classes of disintegrators, but which, nevertheless, in the known constructional forms yield a very low efficiency. According to the principle upon which hitherto the construction of such ball-mills has been based, 15 the interior surface of the mill-drum is provided with projecting ribs, steps, or such like device, which, in their rotation, with the drum, raise the balls until they drop out of the recesses so formed and on to the 20 material which is to be crushed. These ribs or other projections leave dead spaces which are lost to the process of disintegration. By increasing the height of such ribs, 25 not only are the dead spaces equally increased but the ribs will also lift an increased amount of material out of reach of the disintegrating action. Furthermore the mill cannot be worked at anything like high speed, as, if such were the case, the balls 30 would receive a flinging impetus and thus be violently thrown against the bare grinding projections, while concurrently the grist would be lifted too high. This should be avoided because when the material is thus 35 raised by the ribs or projections, the center of gravity is considerably displaced with the result that a very high expenditure of power, in comparison to the attained grinding efficiency is required.

40 According to the present invention the mill-drum may have an absolutely plain inner surface, as the balls are raised by magnetic force excited from the interior and when they have reached any desired height, 45 the attractive power is automatically cut out, so that the balls are released and may fall down unhindered on the material they are intended to crush.

In the accompanying drawings Figure 1 50 shows an example of a constructional form of ball mill according to this invention. Fig. 2 shows a modification. Fig. 3 is an example of a ball mill of the kind hitherto in use. Fig. 4 shows in transverse section 55 an example of a preferred form of ball mill according to the present invention. Fig. 5

shows the same in longitudinal section. Fig. 6 shows diagrammatically an arrangement of automatic switches for magnetizing and de-magnetizing the electromagnets. 60

Referring to Fig. 1 in this example the cylindrical mill-drum is formed by metal plates *a*, set together longitudinally which during the rotary motion of the drum pass in front of stationary electro-magnets *b*, the latter being so placed as to affect the said plates mainly during the rising half of their rotation and by the influence of which they become secondary poles and attract the balls or weights until they reach point *c*, when 70 getting beyond the influence of the magnets they lose their power of attraction and allow the balls to drop.

Fig. 2 is an example of modified constructional form. In this case a number of 75 electro-magnets are arranged in a circle, so as to embrace the whole circumference of the mill-drum and to rotate with the same. Midway between each pair of magnets the coil is reversed as at *d*. Each second metal 80 plate *e* thus forms a pole-shoe for one pole of the magnetic system, the intermediate metal plates *f*, then becoming effective opposite poles. Each coil *g*, is separately energized. For this purpose the conductors are 85 connected to brushes *h*, which are adapted to slide on a stationary contact ring, *i*, and a similarly stationary segment *k*. The length of the latter is determined by period the magnetic field is desired to last, that is to 90 say the current continues to flow through the several coils for such period as the circuit may be closed by contact of the brushes *h*, with the ring *i*, and the segment *k*, respectively. A number of segments *k*, of 95 varying lengths for each of the coils, might be arranged in such a way that the respective brushes *h*, maintain contact with the several coils for varying periods, (corresponding to the varying lengths of the 100 segments) and consequently the balls are released, not in one vertical plane, but over the whole width of the layer of grist.

In the example shown in Figs. 4, 5, 6, the magnets *l* are arranged in five rows of four 105 magnets in each row and are passed through holes in the drum *m* and fixed in position by heads *n* on their inner ends and screw bolts *o* on their outer ends, which bolts pass through bars *p* connecting the magnets of 110 each row, such bar being supported by a casting *q* the lower edge of which rests upon the

face of the drum. The magnets are preferably insulated from the drum by sleeves *r* of suitable material. The parts of the drum between the rows of magnets are perforated for the sifting away of the finely ground particles which, after a further sifting through an outer drum *s*, fall into the discharge hopper *t*. The rough material is fed into the mill through the hopper *u* and passes into the drum through a worm-lined tube *v* which is an extension of the cover plate *w* on one end of the drum and revolves therewith in a bearing *x*. The driving shaft *y* is fixed into the opposite cover plate *z*. In this example the contact strips (shown in Fig. 6) are arranged in the form of concentric segments 1, 2, 3, 4, 5, and a ring 6, upon a disk of insulating material adapted to revolve with the drum upon the same axis. Each of the segments is electrically connected with the negative pole of the battery, the magnetic coils forming part of the circuits. A stationary conducting bridge piece 7 bears contact brushes 8, 9, 10, 11, 12, 13, while the ring 6 is connected with the positive pole of the battery. As the drum revolves one or other of the segments passes under its brush and the corresponding circuit is closed by the connecting bridge thus energizing the row of magnets in that particular circuit. When that segment has completed its passage under the brush the circuit is automatically re-opened and the magnets de-magnetized. The segments are so arranged that each of them begins to pass under the brush when the corresponding row of magnets is in position 15 and completes its passage when the row has nearly arrived at position 18. The balls will thus be carried through about half a revolution and dropped from nearly the highest level. In arranging the coils it is desirable that they should alternate in direction of winding so as to form alternate magnetic poles and thus provide the greatest efficiency.

A comparison between Fig. 3 and Figs. 1, 2 and 4, shows clearly what considerable economic advantages may be gained by the new invention; advantages, which may be summed up as follows: 1. The possibility of using a drum having a perfectly plain inner surface enables the center of gravity of the material, which is being disintegrated, to remain more central with the result of a lower expenditure of power. 2. As the balls do not roll back but strike on the grist from any desired height not a lacerating, but as it should be in a ball mill—a breaking action is attained and simultaneously an economy of motive power. 3. Inasmuch as the balls do not roll back, they produce no friction with the interior surface of the drum so that the latter is exposed in a much smaller degree to wear and tear, and may therefore be constructed of lighter material, resulting in

this respect in a saving of motive power, the electric current required for developing magnetism is so small compared with the resulting economy in motive power, that it is hardly worth taking into account. The finished product may be discharged in any known manner, by means of perforations in the metal plates, or through spaces between the metal plates, or on the end face opposite to the feed.

Having thus described my invention what I claim is:—

1. A ball mill comprising in combination a rotatable drum for containing the material to be crushed, iron balls or weights inside said drum, stationary electromagnets facing the inner circumference of said drum or a portion thereof, and adapted to hold the said balls or weights to the inner surface of said drum only until they have been carried nearly to the highest position in the drum, substantially as shown and described.

2. A ball mill comprising in combination, a rotatable drum for containing the material to be crushed, iron balls or weights inside said drum, electromagnets fixed on the outer circumference, means for magnetizing and de-magnetizing said magnets at convenient stages of their rotation with the drum so as to hold the said balls or weights to the inner surface of said drum and to release them when at a suitable height so as to drop upon the material to be crushed, substantially as shown and described.

3. A ball mill comprising in combination, a rotatable drum containing the material to be crushed, iron balls or weights inside said drum, electromagnets set in longitudinal rows and having heads protruding within the said drum, and means for magnetizing and de-magnetizing said magnets at suitable stages of their rotation with the drum.

4. A ball mill comprising in combination, a rotatable drum for containing the material to be crushed, iron balls or weights inside said drum, electromagnets set in longitudinal rows and having heads protruding within the said drum and means for magnetizing and de-magnetizing said magnets at suitable stages of their rotation with the drum, said means consisting of a rotatable disk provided with insulated concentrically disposed contact strips of segmental shape, brushes engaging said strip to energize said electromagnets only during such stages of the revolution of the magnets as are suitable for the purpose of carrying the said balls to the desired height, substantially as shown and described.

5. A ball mill of the class described comprising in combination, a rotatable drum mechanism adapted to contain the material to be crushed, and crushing elements loosely disposed in said drum mechanism, said drum

mechanism being provided with electrical means for attracting and carrying said elements with said mechanism through one period of its rotation and then permitting said elements to fall upon the material, substantially as described.

6. A mill of the class described comprising in combination, a rotatable drum mechanism adapted to contain the material to be crushed and having a smooth interior surface, and crushing elements loosely disposed in said drum mechanism, said drum mechanism being provided with electrical means for attracting and holding said elements against its interior during a portion of its rotation and then permitting said elements to fall by gravity upon the material, substantially as described.

7. A mill of the class described comprising in combination, a rotatable drum mechanism adapted to contain the material to be crushed, and crushing elements loosely disposed in said drum mechanism, said drum mechanism being provided with electrical means projecting into the interior thereof for attracting and carrying said elements with said mechanism through one period of its rotation and then permitting said elements to fall upon the material, substantially as described.

8. A mill of the class described comprising

ing in combination, a rotatable mill drum adapted to contain the material to be crushed, such elements being loosely disposed in said drum, electrical devices carried by said drum, and electrical mechanism for energizing said devices during one period of the drum's rotation to attract and carry said elements above the material and then deenergizing said devices to permit the elements to fall by gravity onto the material, substantially as described.

9. A mill of the class described comprising in combination, a rotatable mill drum adapted to contain the material to be crushed, crushing elements loosely disposed in said drum, electrical devices carried by said drum, and electrical mechanism for energizing said devices during one period of the drum's rotation to attract and carry said elements above the material and then successively deenergizing the uppermost devices to permit said elements to fall by gravity onto the material, substantially as described.

In testimony whereof, I affix my signature in the presence of two witnesses.

HEINRICH OSTWALD.
